METHOD OF MAKING HUB SHELLS AND
LIKE TUBULAR METAL ARTICLES

Harry W. Kranz and Harry H. Bound, Lakewood,
and Jacob S. Fenzel, Cleveland, Ohio, assignors
to The Cleveland Welding Company, Cleveland,
Ohio, a corporation of Ohio

Application June 16, 1930. Serial No. 461,399

4 Claims. (Cl. 29—159.3)

The present invention relates to the manufacture of hub shells for wire wheels and similar tubular articles of varying diameter, and its primary object is to provide a method whereby such hub shells which heretofore have been made of a number of separate pieces, can be formed by properly shaping and forming a single piece of metal, thereby producing a hub shell structure at a much lower cost than has heretofore been possible without in any way sacrificing strength and rigidity.

More particularly our invention contemplates a process which involves the circularizing or tubulating of a flat or substantially flat blank of a suitable metal such as steel, and then working and forming the resulting tube in such a manner as to obtain the proper form of hub shell desired. As above indicated, hub shells for wire wheels have heretofore been made by rolling and forming a tubular blank of suitable metal into a form having terminal flanges, one flange extending inwardly and the other outwardly. Usually in this form of construction, the outwardly directed flange was provided with an annular shoulder adapted to receive a disc-like member which, provided with a central aperture, coacts with the inwardly directed flange on the opposite terminal of the hub in sustaining the hub assembly within such shell and providing a means for securing to the hub the several parts of the wheel hub assembly. This method of forming the hub shell by uniting two separate pieces is unsatisfactory from the standpoint of cost of manufacture as well as the strength of the resultant hub.

The above outlined method of making hub shells has been employed heretofore due to the fact that no successful method has ever been devised whereby the metal in a single tubular blank can be so worked as to form the relatively large radially extending flange on the enlarged terminal of the hub without breaking or splitting such metal during the working thereof.

By the method comprising our invention, a substantially flat blank may be tubulated and welded together along the adjacent edges thereof, which, when formed and worked according to the method comprising our invention, will be formed into inwardly directed flanges on the terminals thereof for the purpose of securing within the hub the spindle sustaining assembly as well as proper shoulders or annular projections on such hub for the purpose of anchoring the inner ends of the spokes of the wheel. Other objects of our invention will appear as

the description proceeds. To the accomplishment of the foregoing and related ends, said invention, then, consists of the means hereinafter fully described and particularly pointed out in the claims.

The annexed drawing and the following description set forth in detail one approved method of carrying out the invention such disclosed mode, however, constituting but one of the various ways in which the principle of the invention may be used.

In said annexed drawing:

Fig. 1 is an isometric view of a substantially flat blank from which a hub shell is formed by the method comprising our invention; Figs. 2, 3, 4, and 5 show the successive steps in tubulating or circularizing the blank illustrated in Fig. 1; Fig. 6 is a fragmentary sectional view of the blank illustrated in Fig. 5 showing in an enlarged scale the first step in the forming of such tube into a hub shell; Figs. 7, 8, 9 and 10 are fragmentary, sectional views of a portion of the element shown in Fig. 6 illustrating the successive steps in the formation of the hub shell by the method comprising our invention, which will be explained more in detail. It will be noted that Figs. 6 to 10 inclusive are fragmentary views of the hub shell showing only one-half thereof for the purpose of simplifying the drawing and bringing together the several views into proper position to more clearly illustrate the several steps comprising our invention.

In the practice of our invention a substantially flat and generally rectangular blank of the kind shown in Fig. 1 is circularized to produce the open ended hub illustrated in Fig. 2; the ends 1 of this hub are then heated to a sufficiently high temperature while being brought together as illustrated in Fig. 3 and forced into the upset weld 2 as shown in Fig. 4. Following this the flash or burr is removed and the article then presents the appearance shown in Fig. 5. In the next operation of Fig. 6 the diameter of the tube is enlarged from one terminal 3 gradually to an intermediate portion 4 which reduces in diameter rapidly to the tubular portion 5 which is of substantially the same diameter as the original tubular article. The substantially conical portion 6 is then curled and rolled inwardly as most clearly shown at 7 in Fig. 7 after which the portion 7 is flanged inwardly as at 8 in Fig. 8.

The next step in the method comprising our invention consists in shrinking the annular portion 9 of the tubular element adjacent the en-

larged portion 4 as most clearly shown in Fig. 9. The shrinking of the portion 9 may be accomplished simultaneously with the inwardly flanging of the terminal 10 of the tubular article. The next step in the formation of the finished hub shell is to flange out the inner periphery of the inwardly directed flange 8 into an axially extending flange 11 as most clearly shown in Fig. 10. The axially directed flange 11, along with the inwardly directed flange 10, are then in the proper form to receive the spindle-supporting structure on which the hub shell is mounted. The enlargement of the portion 4 along with the annular shrinking of the member as at 9 produces oppositely directed annular shoulders on the hub which serve as anchorages for the inner ends of the wire spokes, is well known to those familiar with the art.

The above explained operations can be effected by any suitable apparatus, for example, the blank shown in Fig. 1 can be sheared to the desired size and shape in a punch press or by means of any other machine adapted to this end. The hoops shown in Figs. 2 and 3 can be produced on a rolling machine having three pyramidically arranged rolls, or it may be formed by bumping or rounding on a press or bulldozer between dies. The ring illustrated in Figs. 4 and 5 is preferably produced by electric welding, the burr or flash incident to the welding being removed by shearing or otherwise to produce a smooth finish. After the burr or flash has been removed by shearing it may be necessary to smooth out slight imperfections necessarily incidental to such shearing by longitudinally rolling the welded seam under pressure rolls which will force such metal into a smooth seam, although slightly deforming the circular blank into a flat area as most clearly shown in Fig. 5. This slight area is, however, in no way detrimental to the subsequent operation included in the method comprising our invention, such flat portion being easily rounded out in the subsequent operations.

The enlargement of the diameter of the tubular article from one terminal to an intermediate portion thereof, as illustrated in Fig. 6, may be accomplished in a sizing machine and the curling of the substantially conical terminal into the form illustrated in Fig. 7 may be most advantageously effected in a press. A press of suitable capacity and proper dies may also be employed for the purpose of flattening the curled terminal of the structure illustrated in Fig. 7 to the form shown in Fig. 8. A rolling machine having suitably arranged rolls may be employed for the purpose of shrinking the annular portion 9 as illustrated in Fig. 9, such rolls also having associated therewith, suitable rolls which will inwardly flange the terminal 10. After the article has been formed as illustrated in Fig. 9, the axial flanging or formation of the flange 11 may most advantageously be accomplished in a press which will force the metal into such flange without splitting or otherwise deteriorating the metal comprising such flange.

From the above description of one form of our improved method, it will be apparent that the enlargement of the diameter of the tube gradually effects the proper distribution of the metal from one terminal to an intermediate portion

thereof, which enables such substantially conical terminal to be curled into a relatively large inwardly directed flange without breaking or ruffling the metal. The thin portion of the tube produced by the enlarging of the diameter thereof occurs at a point having the greatest radius, therefore in no way detracting from the strength of the finished product. The shrinking of the other terminal of the tube provides an increased thickness of the metal in the areas of short diameters thereby producing the proper strength which serves as an anchorage for the inner ends of the spokes of the wheel.

It will be seen that, by employing the above outlined method of forming tubular articles of varying diameter, a hub shell for wire wheels may be manufactured from a single element of stock with a minimum number of operations without any sacrifice of strength and rigidity of the finished shell. By employing this method, the use and assembly of separate items is entirely obviated thereby reducing the cost of manufacture and also providing a hub shell structure which is superior in strength to any made by methods heretofore employed.

Other modes of applying the principle of our invention may be employed instead of the one explained, change being made as regards the methods herein disclosed, provided the step or steps stated by any of the following claims or the equivalent of such stated step or steps be employed.

We therefore particularly point out and distinctly claim as our invention:

1. The method of making hubs and the like which comprises providing a tube, enlarging the diameter of such tube from one terminal gradually to an intermediate portion thereof, contracting the metal beyond the enlarged portion by inwardly flanging such terminal, annularly shrinking a portion of such tube, and inwardly flanging the other terminal.

2. The method of making hubs and the like which comprises providing a tube, enlarging the diameter of such tube from one terminal gradually to an intermediate portion thereof, contracting the metal beyond the enlarged portion by inwardly flanging such terminal, annularly shrinking a portion of such tube adjacent said enlarged portion, and inwardly flanging the other terminal.

3. The method of making hubs and the like which comprises providing a tube, enlarging the diameter of such tube from one terminal gradually to an intermediate portion thereof, contracting the metal beyond the enlarged portion by inwardly flanging such terminal, annularly shrinking a portion of such tube, inwardly flanging the other terminal, and axially flanging said first named flange.

4. A method of making hubs and the like, which comprises expanding the diameter of a tubular blank at an intermediate portion without thereby materially shortening the axial length, shrinking and thickening the end thereof, shrinking and thickening the portion of the tubular blank at the other side of the enlarged intermediate portion, and shrinking and thickening the remaining free end.
